CLAIM

The ornamental design for an interchangeable jewelry key, as shown and described.

DESCRIPTION

FIG. 1 is a top, left perspective view of an interchangeable jewelry key;

FIG. 2 is a right elevation view thereof;

FIG. 3 is a left elevation view thereof;

FIG. 4 is a bottom elevation view thereof;

FIG. 5 is a top elevational view thereof;

FIG. 6 is a front elevational view thereof; and,

FIG. 7 is a rear elevational view thereof.

The broken lines in the drawings represent portions of the interchangeable jewelry key that form no part of the claimed design. The other broken lines showing text indicia represent environmental subject matter only and form no part of the claimed design.

1 Claim, 3 Drawing Sheets
